UNITED STATES PATENT OFFICE.

ELIJAH J. EMERY, OF POTTSVILLE, PENNSYLVANIA.

GARMENT.

1,192,288.

Specification of Letters Patent. Patented July 25, 1916.

Application filed October 18, 1915. Serial No. 55,697.

To all whom it may concern:

Be it known that I, ELIJAH J. EMERY, a citizen of the United States, residing at Pottsville, in the county of Schuylkill and State of Pennsylvania, have invented new and useful Improvements in Garments, of which the following is a specification.

The present invention relates to a one-piece garment, for working men, and one of the objects of the invention is to construct a combined blouse and overall which may be easily and quickly positioned upon the wearer.

Another object of the invention is to construct an outer or working garment which shall include a back and body portion having an integral leg portion, the body portion having attached thereto below the waistline thereof a front or blouse, the members of which overlap and being removably connected, the leg portion as well as the body of the crotch thereof having secured thereto front leg portions which include an apron member; the said apron member adapted to be folded over and to be attached to the front or blouse portion of the garment above the waistline thereof, while the free ends of the front leg portions are removably connected with the rear leg portions, thus producing a garment which, while, as stated, may be easily and quickly arranged upon the person of the wearer, permits of the same being easily washed, dried and ironed.

With the above and other objects in view, the improvement resides in the construction, combination and arrangement of parts set forth in the following specification and falling within the scope of the appended claims.

In the drawings: Figure 1 is a perspective view of a garment constructed in accordance with my invention, Fig. 2 is a similar view of the apron lowered and the front members of the blouse opened, Fig. 3 is a perspective view of the apron brought away from the blouse and the front legs moved away from the rear legs, Fig. 4 is a sectional view approximately on the line 4-4 of Fig. 1, Fig. 5 is a sectional view approximately on the line 5-5 of Fig. 1, and Fig. 6 is a sectional view approximately on the line 6-6 of Fig. 1.

The improved garment is constructed of some suitable cloth adapted for hard wear, as the said garment is designed for the use of mechanics and the like, and the garment

includes essentially a back body portion 1, the same preferably comprising two sections which are centrally stitched together. The stitches connecting the back 1 terminate at 60 the crotch 2 of the garment and the said back includes members extending from the said crotch 2 providing the rear leg sections 3. The back body portion, below the collar 4, is provided with the arms 5, and the said arms have their outer members secured to the front body portions 6-6 which are stitched to the back body, the said front body portions 6-6 being connected with the back body above and in a line with the 70 crotch 2 thereof. The body members have their lower edges curved, as at 7, and their inner edges vertically straight and adapted one to overlap the other. One of the said edges of one of the body portions 6 has secured thereon the male members 8 of a clasp, the edge of the opposite front body member 6 having its inner face provided with female members which are adapted to receive the male members 8. The front body members 6 are provided approximately in a line with the central portion of the sleeves 5 with male members 10 similar to the male members 8, and the outer edges of the rear leg sections 3 are provided with similar male 35 members 11. The front body portions 6 above the line of the crotch 2 are likewise provided with a similar male securing member 12.

Stitched to the inner edge of the leg sections 3 as well as to the crotch 2 of the body are the front leg members 13-13, the said members being provided with an extension forming an apron 14, and the inner edges of the leg sections 13 are provided with female 95 catch members 15 which are adapted to engage with the male members 11 and 12 when the garment is arranged upon the body of the wearer. Likewise the apron 14 at the upper corners thereof is provided with 100 catch members 16 which receive the catch members 10 upon the front body portion or blouse member 6 when the apron is secured over the front of the garment.

The garment may be provided with any 105 number of pockets upon the central portion of the apron as well as upon the body of the apron adjacent the front leg portion formed with the said apron, the said pockets being indicated by the numerals 17 and 18, 110 and likewise the rear face of the body member at the seat of the garment may be pro-

vided with similar pockets 19 and 20. One of the rear leg members 3 upon its outer face is provided with two parallel spaced pockets 21 and 22, the upper pocket 22 being 5 of a greater depth than the lower pocket 21, so that a rule, or similar measuring instrument, may be first inserted in the pocket 21 and allowed to drop by gravity to within the pocket 22.

10 From the above description, taken in connection with the accompanying drawings, the simplicity of the device, as well as the advantages thereof will, it is thought, be perfectly apparent to those skilled in the 15 art to which such invention appertains without further detailed description.

Having thus described the invention, what I claim is:

1. In a combined overall and blouse, a 20 back including a body portion and leg portions, front body portions secured to the edges of the back body portion above the waistline of the said body portion, front leg portions secured to the inner edges of 25 the rear leg portions and to the crotch of the back body portion, said front and rear leg portions having free outer edges, said front leg portions extending above the waistline of the rear body portion, an apron 30 member formed with the front leg portions, means for removably securing the apron to the front body portions, and means for removably connecting the free edges of the front leg sections to the free edges of the 35 rear leg portions throughout their entire length and to the rear body portion above the waistline thereof.

2. In a garment for the purpose described,

a back including a body portion and leg portions extending from the crotch of the back and below the waistline of the said back, front body portions secured one to each of the outer edges of the rear body portion above the waistline and in a line with the crotch thereof, said front and body portions having their lower edges rounded toward the outer edges thereof, and one of the said outer edges adapted to overlap the outer edge of the second member, clasps for securing the overlapping edges, one of said members being arranged upon the outer faces of each of the overlapping members, outer leg members secured to the inner edges of the inner leg members at the crotch of the back body portion of the garment, said 55 front and rear leg members having free outer edges, said outer leg members extending above the waistline of the rear body portion, clasp members upon the free edges of the front and rear leg sections and upon the body member above the waistline thereof for temporarily connecting the outer leg sections to the rear leg sections throughout their entire length and to the rear body, said front leg sections having extending 60 apron portions, said apron having clasp members engaging with the clasp members, upon the members comprising the front body portions.

In testimony whereof I affix my signature 70 in presence of two witnesses.

ELIJAH J. EMERY.
